UNITED STATES PATENT OFFICE.

MARY J. WILLIS, OF KANSAS CITY, MISSOURI.

DESIGN FOR A GAS-RANGE.

SPECIFICATION forming part of Design No. 27,485, dated August 3, 1897.

Application filed August 25, 1896. Serial No. 603,907. Term of patent 7 years.

To all whom it may concern:

Be it known that I, MARY J. WILLIS, a citizen of the United States, and a resident of Kansas City, Jackson county, State of Missouri, have invented and produced a new and original Design for a Gas-Range, of which the following description, taken in connection with the drawings herewith accompanying, is a specification.

Referring to the drawings, Figure 1 is a front elevation of a gas-range, showing my design; and Fig. 2 is a plan view of the same.

a represents the body of the stove, the upper surface of which when viewed in front elevation, as in Fig. 1, is in two different horizontal planes, with each part denoted at *a'* and *a''* terminating at their inner end at a point about midway between the ends of the stove, as shown. In the face of the stove, at a point below the lower upper surface *a''*, where the cooking-burners *b* are located, and within the space between a vertical line from

the ends of such lower surface *a''*, is an open rectangular space *c*. At one side of the latter and within the space between a vertical line from the ends of the higher upper surface *a'* appear two other openings *d* and *d'*, arranged one above and one below the usual hot-water coils, with an intervening space *d''* between the same. Projecting from the lower side of the stove-body *a* as thus designed are the legs *e*, which latter are of considerable length, so that the body of the stove stands well up from the floor.

What I claim is—

The design for a gas-range, as herein shown and described.

Signed at Kansas City, Jackson county, Missouri, on the 22d day of August, 1896.

MARY J. WILLIS.
